(No Model.)

M. HYNES.
ELECTRICAL ANNUNCIATOR DROP.

No. 425,078.

Patented Apr. 8, 1890.

Martin Hynes.

INVENTOR.

ATTORNEY.

UNITED STATES PATENT OFFICE.

MARTIN HYNES, OF BOSTON, MASSACHUSETTS.

ELECTRICAL ANNUNCIATOR-DROP.

SPECIFICATION forming part of Letters Patent No. 425,078, dated April 8, 1890.

Application filed December 14, 1882. Serial No. 79,255. (No model.)

To all whom it may concern:

Be it known that I, MARTIN HYNES, of the city of Boston, county of Suffolk, and State of Massachusetts, have invented certain new and useful Improvements in Electrical Annunciator-Drops for Telephonic Signals; and I do hereby declare that the following is a full and correct description of the same, reference being had to the accompanying drawings, and to the letters of reference marked thereon, which form a part of this specification.

Similar letters of reference are used to indicate like parts in all the drawings accompanying this specification.

The object of my invention is to provide an electrical annunciator-drop particularly adapted for use in the central office of a telephonic exchange.

Figure 1 is a side view of my invention. Fig. 2 is a top view of the same. Fig. 3 is a front end view with the shutter-drop down, and Fig. 4 is a rear end view.

A is the base on which my annunciator rests, and B is the base-bar of the annunciator.

C is the shutter-drop provided with the metallic pin c, which is firmly soldered into the shutter-drop.

D is the adjusting-post on the front end of the annunciator, which is provided near its upper end with a circular slot a, through which the armature E passes. The post D is also provided with the adjusting-screws b and d, which operate through its upper and bent portion.

The adjusting-screw e, near the lower portion of the post D, is used for adjusting the shutter-drop C in a perpendicular position or at any desired angle.

The armature E is provided with the spring F, which is screwed to the upper side of the armature.

G is a Y-shaped post at the rear end of the base-bar B, to which the rear end of the armature E is pivoted.

The spools H and H' form the coils of the electro-magnet.

The binding-posts I and I' are connected, respectively, with the base-bar B and the local-battery spring K.

The front end of the armature E is notched on its upper side at g, and with this engages the shutter-drop C when it is in an upright position.

The object of the adjusting-screws b and d is obvious—to regulate the armature E in its relation to the shutter-drop C and to the electro-magnet. By means of these adjusting-screws the armature can be adapted to the electric currents as received from longer or shorter lines.

When a subscriber signals the central office of the telephonic exchange, the circuit through the annunciator is closed. This causes the armature to vibrate, and thus releases the shutter-drop, which immediately falls down. In falling down the metallic pin c of the shutter-drop comes in contact with the local-battery spring K, which causes the bell to ring, and thus gives notice to the central office that a subscriber has called, and the number on the now-exposed face of the shutter-drop indicates the source of the call.

Having now fully described my invention, what I claim, and desire to secure by Letters Patent, is—

The armature E, provided with the spring F and the shutter-drop C, in combination with the post D, provided with the adjusting-screw e, to regulate the position of the shutter-drop C, the adjusting-screws b and d, the post G, and the electro-magnet H H', substantially as shown and described, and for the purposes herein set forth.

In testimony that I claim the foregoing I have hereunto set my hand this 9th day of December, 1882.

MARTIN HYNES.
